UNITED STATES PATENT OFFICE.

JOSEPH N. MAHONEY, OF BROOKLYN, NEW YORK.

ELECTROMAGNETIC APPARATUS.

SPECIFICATION forming part of Letters Patent No. 777,039, dated December 6, 1904.

Original application filed January 21, 1904, Serial No. 190,061. Divided and this application filed March 19, 1904. Serial No. 198,982. (No model.)

To all whom it may concern:

Be it known that I, JOSEPH N. MAHONEY, a citizen of the United States, residing in the borough of Brooklyn, county of Kings, State 5 of New York, have invented certain new and useful Improvements in Electromagnetic Apparatus, of which the following is a specification.

This invention is shown in the form of a 10 tractive electromagnet designed to perform work—as, for instance, in an electromagnetic car-brake system to apply the shoes to the wheels—and is illustrated in connection with mechanical appliances whereby the pressure 15 between the braking-surfaces so obtained or the strain exerted by the magnet may be retained by mechanically-acting locking devices which, according to the requirements of any 20 system to which such an electromagnet may be applied, may be released, as desired, either automatically or otherwise.

The invention, as will be apparent to those skilled in the art, is applicable to many uses, and that shown is merely illustrative of one 25 use to which the invention may be applied either with or without the locking or retaining devices.

In the accompanying drawings, Figure 1 is a 30 vertical section on the line 2 2 of Fig. 2. Fig. 2 is a front elevation of the same, the stop or buffer bar shown in Fig. 1 being, however, omitted. Fig. 3 is a side elevation, partly broken away to show a detail of the retaining mechanism; and Fig. 4 is an end elevation. 35

The apparatus comprises an outer body or shell *a*, of magnetic metal, which may be cast-iron, and within which are disposed the bobbins or windings *b*, three bobbins being shown 40 in this instance, each having two windings *b*' *b*'''. Of course the winding of the apparatus will be adapted to the purpose intended and may consist of wire of unequal gage and length arranged in any desired way. Within 45 the bobbins is a bushing *c*, of non-corrosive and non-magnetic metal—such, for instance, as copper or brass—and within this tube or bushing reciprocates the armature or plunger

d, of superior magnetic metal, such as wrought-iron or cast-steel. The rear head *e* of the 50 shell, which may also be of cast-iron, carries a hollow pole-piece *f*, of wrought-iron or cast-steel, that extends within the winding. The bushing *c* extends, preferably, from the pole-piece *f* to the front opening in the shell. The 55 bore of the pole-piece *f* is of the shape of the frustum of a cone, the smaller diameter of which is at the outer end, and the inner end of the plunger or armature *d* is conical, with the same angle of taper as that of the bore 60 in the pole-piece, but of greater length. The purpose of so shaping the pole-piece and end of the armature is to decrease the area of the air-gap relatively to the decreasing length of the air-gap as the armature moves inward. 65 This is accomplished by permitting the tapered end of the armature to pass beyond the outer or smaller end of the opening in the pole-piece, thereby tending to maintain a constant reluctance in the magnetic circuit, and 70 consequently a uniform pull throughout the travel of the armature. This arrangement also increases the general efficiency of apparatus of this character by increasing the area of the air-gap relatively to the cross-section 75 of the area of the armature.

Attached to the front or outer end of the armature is the jaw or clevis *g*, provided with pin *g*' for attachment of the part on which the pull of the armature is to be exerted. The 80 rear plate or end piece *e* is formed with an opening *e*' for passage of the wires and is preferably covered by a hood *e*''. A segmental stop or retaining plate *h* is bolted to the front end of the shell and serves to hold the bushing 85 *c* in position. In Fig. 1 I have shown a stop or buffer for limiting the outward movement of the armature. It consists of three arms *i*, attached at the three threaded openings *i*' *i*'' *i*''' and connected with or uniting in a head or 90 buffer *i**, against which abuts the clevis or jaw *g* or any other part that may be provided projecting from the plunger.

The upper face of the armature is flattened, and resting thereon is an angular or L-shaped 95 shoe *j*, located between the shell and a block

k, bolted to the front face and extending inwardly into a chamber *k'*, formed in the front of the shell. A steel roller *m* (or one or more steel balls) lies loosely within the angle of the 5 shoe *j* and is normally urged inwardly by two pins *n*, acted upon by coiled springs seated in sockets in the block *k*. Resting on the roller is a wedge-block *o*, which in the construction shown is normally pressed downwardly on the 10 roller by a cam *p*, attached to or forming part of a shaft *q*, relatively mounted in bearings *q' q'*. To this cam-shaft is secured a lever-arm *r'*, against which bears a plunger *s*, seated in a casing *s'* and normally urged forwardly 15 by a coiled spring *s''*, adjustment of the spring being afforded by means of a screw *s'''*, working in the head or end of the casing *s'*.

The strain of the load or the reactionary pull of the brake-gear in a braking system 20 would on cessation of or sufficient diminution of current in the windings *b* retract the armature were it not that the roller *m* bears upon the inclined face of the wedge-block, which is positively held by the cam, thereby pressing 25 the shoe *j* against the flattened face of the armature and locking it against withdrawal. This locking of the armature may be released in any appropriate way, either automatically or otherwise. The organization illustrated, 30 however, contemplates its release automatically by passage of current through the windings of a magnet *u*, which may be of the same general construction as the magnet already described and on the side of the shell of which 35 it may be mounted. The armature or plunger *u'* of this release-magnet is normally retracted, permitting the plunger *s* to hold the wedge-block in contact with the locking-roller; but when current passes in the coils of the 40 release-magnet and its armature is attracted the lever-arm *r'*, with which it is connected by a pin-and-slot connection *u''* or otherwise, is drawn forward to rock the shaft *q* and carry the rise of the cam *p* away from the upper 45 surface of the wedge-block *o*, thereby unlocking or releasing the armature *d*, the wedge-block then being free to rise. Of course the locking-roller might rest directly on the flattened upper face of the plunger or armature 50 *d*; but I prefer to employ a shoe having a flat face bearing on the flattened face of the armature, as the shoe may be replaced in the event of wear thereof and danger of the flattened face of the armature being injured is 55 obviated.

This is a division of my application, Serial No. 190,061, filed January 21, 1904, for electric brakes for vehicles.

I claim as my invention—

60 1. An electromagnet comprising a winding and a shell of magnetic metal inclosing it, a pole-piece projecting within the winding and having through it an opening with inclined walls, and an armature reciprocable within the

winding and having its inner end tapered to 65 conform to the taper of the opening in the pole-piece but of such length as to extend through and beyond it.

2. An electromagnet comprising a winding and a shell of magnetic metal inclosing it, a 70 pole-piece projecting within the winding and having through it an opening with inclined walls, an armature reciprocable within the winding and having its inner end tapered to conform to the taper of the opening in the 75 pole-piece but of such length as to extend through and beyond it, a wedge-block, a roller interposed between it and the side of the armature, a spring device normally urging the roller out of engagement with the inclined 80 face of the wedge-block, and means for forcing the wedge-block against the roller to thereby lock or retain the armature in any position to which it may be attracted.

3. An electromagnet comprising a winding 85 and a shell of magnetic metal inclosing it, a pole-piece projecting within the winding and having through it an opening with inclined walls, an armature reciprocable within the winding and having its inner end tapered to 90 conform to the taper of the opening in the pole-piece but of such length as to extend through and beyond it, a wedge-block, a roller interposed between it and the side of the armature, a spring device normally urging the 95 roller out of engagement with the inclined face of the block, a rocking shaft carrying a cam bearing on the wedge-block, a spring tending to force the wedge-block down on the roller and an electromagnet acting in opposition to the spring. 100

4. An electromagnet comprising a winding, an armature reciprocable within the winding, a wedge-block, a locking-roll interposed between it and the armature, means for normally 105 urging the inclined face of the block against the roll to lock the armature in its attracted position, and means for releasing the pressure of the block upon the roll to permit retraction of the armature. 110

5. An electromagnet comprising a winding, an armature reciprocable within the winding, a wedge-block, a locking-roll interposed between it and the armature, means for normally 115 urging the inclined face of the block against the roll to lock the armature in its attracted position, and an electromagnet acting to release pressure of the block upon the roll to permit retraction of the armature. 120

6. An electromagnet comprising a winding, an armature reciprocable within the winding, a wedge-block, a locking-roll and shoe in which it is seated interposed between the side of the armature and the inclined face of the wedge-block, means for normally urging the inclined 125 face of the block against the roll to lock the armature in its attracted position, and means for releasing the pressure of the block upon

the roll to permit the retraction of the armature.

7. An electromagnet comprising a winding and a shell of magnetic metal inclosing it, a
5 pole-piece extending within the winding and having an opening with inclined walls, and an armature reciprocable within the winding and having its inner end tapered to conform to the

taper of the opening in the pole-piece and adapted to extend through it.

In testimony whereof I have hereunto subscribed my name.

JOSEPH N. MAHONEY.
